UNITED STATES PATENT OFFICE.

EARL J. BRACKEN, OF BUTTE, MONTANA.

TAG FASTENER.

Application filed March 27, 1923. Serial No. 628,071.

To all whom it may concern:

Be it known that I, EARL J. BRACKEN, a citizen of the United States, residing at Butte, in the county of Silver Bow, State of Montana, have invented certain new and useful Improvements in Tag Fasteners; and I do hereby declare the following to be a full, clear, and exact description of the invention, such as will enable others skilled in the art to which it appertains to make and use the same.

This invention relates to new and useful improvements in tags and particularly to means for attaching tags to packages.

One object of the invention is to provide a tag attaching means which can be applied to the cord, wire, or other means employed for tying a package, without the necessity of passing a piece of cord through the eyelet of the tag, or of tying the tag to the package.

Another object is to provide a device of this character which is strong and durable, and which is simple in construction and which can be manufactured at a low cost.

Other objects and advantages will be apparent from the following description when taken in connection with the accompanying drawing.

In the drawing:

Figure 1 is a perspective view of a tag attached to the binding cord of a package, and embodying the present invention, in one form thereof.

Figure 2 is a perspective view of another form of the snap-hook employed for attaching the tag to the package.

Figure 3 is a perspective view of still another form of the snap-hook.

Referring to the accompanying drawing, and particularly to Figure 1, 10 represents the tag, which may be formed from heavy paper, cardboard, linen, or other suitable material and having the eyelet 11 in one end.

Engaged around the shank of the eyelet 11, and held by the clinched head of the eyelet, is the eye portion 12, of the wire stem of the tag attaching means. The other end of the wire is formed into several coils 13, and thence longitudinally, as at 14. The wire end is then rebent at 15, extended back in approximately parallel relation to the portion 14, formed into a curved bight 16, and thence outwardly in parallel relation to the

rebent portion 15, through the coils 13, and then outwardly to lie against the inner

curved portion of the bight 16, the last-named portion being designated by the numeral 17, and constituting the locking tongue of the device.

In applying the device to a package, the stem and tags are grasped in the hand and the tongue pressed against the binding twine of the package and given a slight longitudinal movement to cause the binding twine to pass the terminal of the tongue and engage within the curved hook portion of the device, which lies between the portions 14 and 15. Thus applied to the binding twine, the tag is firmly affixed and cannot become accidentally displaced or removed.

In Figure 2, the stem 18 is extended outwardly and thence rebent inwardly and formed with the bight 19, which is continued to form the other leg 18', which is extended inwardly and coiled around the stem 18 at 20, and thence extended outwardly to light against the bight 19, to form the locking tongue.

In Figure 3, the form of the device is much simpler than the other forms. In this form the stem 21 is extended outwardly at 22, rebent and curved at 23, and extended inwardly toward the stem at 24, in the form of a knuckle or knee. The wire is then extended away from the stem at an acute angle, as shown at 25, and then extended inwardly at 25', to the stem, and then continued in longitudinal contacting relation to the stem for a short distance, as shown at 26. The portions 25 and 25' are connected, at their outer ends, by the bight 27, and said portions, in combination with the bight, form a hook while the portion 26 serves as the locking tongue. The binding twine of the package is passed between this hook and the stem 18, until it snaps past the member 26, and enters the curved portion 23.

There is thus provided a tag attaching means whereby the necessity of applying twine to the tags, and then tying the twine to packages, is completely obviated, as the device, which is in the general form of a snap-hook, is simply engaged in snapping and locking relation to the twine. This will conserve the time and labor in applying tags to packages, and will be especially useful in shipping places where large numbers of packages are sent out each day.

What is claimed is:

A tag fastener formed from a single length of wire bent intermediate its length to form

a hook loop, one end of the loop being extended to form a shank having an eye adapted to be secured within an end of a tag, the other end of the loop being coiled around 5 the shank intermediate the length of the shank and extended into contact with the bight of the loop hook.

In testimony whereof, I affix my signature, in the presence of two witnesses:

EARL J. BRACKEN.

Witnesses:

FRANK W. HASKINS,
JOSEPHINE RICKER.
